UNITED STATES PATENT OFFICE.

MARK B. HARRIS, OF DETROIT, MICHIGAN, ASSIGNOR TO GENERAL MOTORS CORPORATION, OF DETROIT, MICHIGAN, A CORPORATION OF DELAWARE.

RESERVE-FUEL-SUPPLY DEVICE.

Application filed November 14, 1921. Serial No. 514,961.

The invention relates to devices for insuring a reserve supply of liquid particularly in connection with the fuel tanks of automobiles, and in like relations, and its principal object is to provide a device which shall be extremely simple in construction and operation, inexpensive in manufacture and assembly and highly efficient for the purpose for which it is designed.

10 In the operation of automobiles it often happens that the supply of fuel in the fuel tank becomes entirely exhausted, through inattention or forgetfulness on the part of the operator, and the circumstances are frequently such as to render the obtaining of a new supply a matter of great inconvenience. It is therefore of advantage to provide means whereby, after the normal fuel supply is exhausted, a reserve may be easily 20 rendered available sufficient to maintain the engine in operation for at least a few miles travel. In accordance with my invention such a reserve supply is provided for by changing the level from which fuel in the 25 main tank is drawn, the mere adjustment of a lever or the like being sufficient to change the adjustment of the fuel withdrawing device from the normal level, at which a reserve supply will be left in the bottom of the fuel tank, to the emergency level at 30 which substantially all the fuel may be withdrawn.

In the accompanying drawings,

Figure 1 is a vertical sectional view of a fuel tank having associated therewith one form of mechanism in which the invention may be embodied,

Figure 2 is an enlarged sectional view showing a portion of the mechanism,

Figure 3 is a plan view of a portion of the structure shown in Figure 1,

Figure 4 is a section corresponding to Figure 2 but showing a slightly modified form, and

Figure 5 is a perspective view of a detail of the structure shown in Figure 4.

Referring to the drawings, and especially to Figures 1, 2 and 3, 10 indicates a receptacle which may be of any desired character but is shown as of a form commonly employed for fuel tanks of automobiles. A filling opening is provided at 11 which opening is covered by the filler cap 12.

At a suitable location on the exterior of

the tank 10 is secured the head 13 in which is formed the chamber 14 opening to the interior of the tank. A pipe 15, communicating with the chamber 14, as by passage 16, leads to any usual or suitable form of liquid fuel pumping mechanism, as, for example, to a vacuum tank mechanism. The lower part of chamber 14 adjacent to the point of communication with the passage 16 is of conical form and contains a similarly shaped plug 17. The plug is provided with an axial bore 18 communicating with a transverse passage having opposite openings 19 and 20, and the said openings being so situated as to be capable of being brought into register with the passage 16. The plug 17 is formed upon or otherwise rigidly connected to a rod 21 the upper end of which extends outside the chamber 14 and is bent laterally to provide a handle 22. A coiled spring 23 may be mounted above the plug 17 and arranged to be compressed by a screw cap 24, the latter being centrally apertured to permit the passage therethrough of the rod 21 and closing the upper end of the chamber 14.

Secured to the lower end of plug 17 is a tube 25 the interior of which communicates with bore 18. The lower portion of the tube is bent as indicated at 26 or otherwise formed so that the intake end or opening, 27, is offset from the axis of the plug 17. The head 13 is mounted, as shown, on an inclined portion of the tank wall, or is so shaped that the axis of the tube and supporting plug 17 is inclined to the vertical. As a result, the position of the bent or offset lower end of the tube 25 may be varied by rotation of the plug and the parts rigidly connected thereto. For example, with the parts in the position shown in full line in Figure 1 the lower end of the tube will be near the lowest point of the interior of the tank in which position substantially all the fuel may be withdrawn, opening 20 being in register with passage 16; whereas, if the handle 22 be turned through an angle of 180° thereby positioning the parts as indicated in Figure 2, and in dotted lines in Figure 1, bringing opening 19 in register with passage 16, the lower end of the tube will be at a somewhat higher level, thus preventing withdrawal of fuel below the level

2
indicated at 28. If the parts are normally so positioned as to draw fuel from the higher level then the remainder of the fuel in the tank will constitute a reserve supply which 5 may be rendered available by simply turning the handle 22. The amount of fuel thus retained in reserve will vary with the dimensions of the tank, the amount by which the intake opening is offset from the axis of 10 rotation of the tube, and the inclination of the axis to the vertical; and in the application of the invention to a gasoline tank for use with an automobile power plant, the proportions, of course, will be preferably so 15 determined as to insure a reserve of fuel ordinarily sufficient to enable the vehicle to be driven a distance of several miles.

If desired, the head 13 may be mounted in proximity to the filling opening so that 20 the handle 22, when set in a position to permit withdrawal of the reserve supply, will extend over the filling cap as shown in Figure 3. In order to remove the cap it becomes necessary therefore to first adjust the 25 parts to a position for withdrawing fuel from the higher level, thereby insuring the proper re-setting of the reserve supply mechanism preliminary to refilling the tank. The parts will be retained in adjusted position by friction under the influence of 30 spring 23.

In the form illustrated in Figures 4 and 5, the head 13' is provided with a cylindrical chamber 14' with which the pipe 15 35 communicates by passage 16'. A plug 17' is formed with an enlarged upper end seated in the chamber 14'. The plug is provided with an axial bore 30, and a transverse diametrical slot 31 in the enlarged upper portion 40 of the plug connects the bore to the passage 16' in either of two positions of adjustment of the plug. A screw cap or plug 32 closes the upper end of chamber 14' and serves to clamp the plug 17' in adjusted 45 position. The tube 25 is secured to the plug 17' as in the form first described. In order to set the tube 25 in the desired position in this embodiment of the invention it is necessary to remove screw cap 32, and rotate the 50 plug 17' by means of a suitable tool inserted in the slot 31, the positioning of the end of the slot in register with the passage 16' serving as an indication of the proper position of adjustment. This form of the device 55 is, of course, less readily adjusted than the form first described, but affords the advantage of being less likely to be tampered with by unauthorized persons.

Various other embodiments or modifications in detail of construction may be made 60 by one skilled in the art without departing

from the scope of the invention as set forth in the following claims:

I claim:

1. In a liquid supply system, a receptacle, 65 a member extending downwardly in the receptacle rotatable about an axis inclined to the vertical, an intake offset from said axis and adapted to be positioned at a higher or lower level by rotation of said member, 70 means on the upper end of the member for rotating the same, a filling opening adjacent to said means, and a closure for said filling opening, said means arranged to be positioned with reference to said closure to prevent removal thereof when the intake is 75 positioned at the lower level.

2. In a liquid supply system the combination of a tank having an opening in the upper portion thereof, a tubular member extending downwardly through said opening and rotatable about an axis inclined to the vertical, said member having an intake offset from its axis of rotation whereby rotation of said member will position said 80 intake at higher or lower levels within said tank, means connected to the upper end of said member for rotating the same, a fitting serving as a closure for said opening and in which the upper end of said member is positioned, and a conduit leading from said fitting through which liquid may be withdrawn. 85

3. The combination of a fuel tank, a pump supply pipe, a plug rotatable about 95 an inclined axis and having passages adapted to communicate with said pipe in two positions of the plug, a tube carried by said plug extending to the lower portion of the tank and having an intake offset from the 100 axis of the plug whereby rotation of the plug will position the intake at different levels in the tank, a handle exterior to the tank for rotating said plug, and means for securing the plug in its positions of rotative 105 adjustment.

4. The combination of a fuel tank, a pump supply pipe, a plug rotatable about an inclined axis and having passages adapted to communicate with said pipe in two 110 positions of the plug, a tube carried by said plug extending to the lower portion of the tank and having an intake offset from the axis of the plug whereby rotation of the plug will position the intake at different 115 levels in the tank, means providing a chamber for enclosing and supporting said plug, a cap adapted to close said chamber and engage and clamp said plug in position.

In testimony whereof I affix my signature. 120

MARK B. HARRIS.
